BY
Albert R. Dutrich
ATTORNEY

UNITED STATES PATENT OFFICE

CHARLES L. DUNHAM, OF WELLSBURG, WEST VIRGINIA

WRENCH

Application filed July 24, 1930. Serial No. 470,462.

My invention relates to wrenches of the pivoted inner jaw type and it particularly has for its object to provide a wrench which may be employed as a pipe and rod wrench over a wide range of pipe and rod sizes (for example from one inch to two and one-quarter inches), a wrench which may be used on round or square rods with equal facility, and a wrench which may be used on square or hexagon nuts.

Further, it is an object to provide a wrench for the purposes stated that is so constructed that it will be self-adjusting to the various sizes of pipes, rods, nuts, etc. on which it is to be used.

Further, it is an object to provide a wrench in which the movable inner jaw has positive bearing on a considerable surface whereby wear on the pivot pin or stud is practically eliminated.

Further, it is an object of the invention to provide a wrench of the type referred to which will effect at least a three-point engagement with the object operated upon and will thus eliminate a serious draw-back now present in wrenches usually used on pipes, i. e. that of eventually cutting through the pipe in places or so marring or weakening the walls of the pipe as to cause leakage to occur after a time.

Further, it is an object to provide a wrench in which the manufacturing factor has been carefully considered and in which the parts have been so designed as to reduce the cost of manufacture to a minimum.

Further, it is an object of the invention to provide a wrench in which the operating end has the general form of a "hand" in side view, the outer fixed jaw constituting a "finger" to overlie the work and the inner fixed jaw-carrying member constituting the "thumb", on the end of which member is mounted the pivoted jaw.

Further, it is an object of the invention to provide a wrench of the character stated in which the crotch of the wrench extends in the same longitudinal direction as the length of the handle thus enabling the tool to work in corners and out-of-way places with ease.

Further, it is an object of the invention to

provide a wrench that is neat in appearance as well as effectual in its operation.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claim, reference being had to the accompanying drawings, in which:—

Figure 1 is a perspective view showing the wrench about to be applied to a horizontal pipe.

Figure 2 is an elevation of the wrench applied to the largest size pipe for turning the same in a clockwise direction (the handle or "arm" being broken away).

Figure 3 is a view similar to Figure 2 showing the wrench applied to the smallest size pipe.

Figure 4 is a view similar to Figures 2 and 3, showing the wrench applied to an octagon nut, in dotted lines showing a square rod in position for having the wrench applied.

Figure 5 is a detail perspective view of the "finger" per se.

Figure 6 is a detail perspective view of the "thumb" carrying member.

Figure 7 is a detail perspective view of the pivoted jaw.

Figure 8 is a detail perspective view of the "wrist" portion of the "arm".

In the drawings in which like numerals of reference indicate like parts in all of the figures, 1 represents the handle or "arm" having the bifurcated "wrist" portion 2 to which the "hand" is secured.

The "hand" comprises the "thumb" and "finger" carrying portion 3, the latter having a flat shank 4 to fit into the bifurcation of the "wrist" portion 2 to which it is secured in any suitable manner as by rivets 5 or other suitable fastenings.

The rigid "finger" 6 is preferably separately formed from the portion 3 and is curved as shown, the operating face being preferably provided with teeth 7.

The member 3 is bifurcated as at 8 to receive the shank 9 of the rigid "finger" 6, the "finger" being secured in place by rivets 10 or other suitable fastenings.

5 The "thumb" 11 is preferably integrally formed with the member 3 and extends laterally and forwardly therefrom, the "thumb" and "finger" being spaced apart to leave a crotch 22 as shown.

10 The "thumb" 11 has its end bifurcated as at 12 and curved to form an outer seat 13 and an inner seat 14, the curvature of the seats being struck on the center or axis of the pivot pin 15 which pivotally attaches the inner jaw 16 to the outer end of the "thumb" 11.

15 The inner jaw 16 is provided with a V-shaped gripping face 17, preferably serrated, and with bearing shoulders 18 to engage the outer curved seats 13 of the "thumb", there being a pivot ear 19 provided on the jaw having an elongated slot 21 for the pivot pin 15. The ear also is provided with a bearing edge 20 to engage the seat 14. The engagement of the shoulders 18 with the bearing seats 13 25 and the engagement of the curved edge 20 with the seat 14 enabling a direct pressure thrust between the pivoted jaw and the "thumb" without placing shearing pressures on the pivot pin or stud 15 and thus avoids 30 wear on the pivot pin or stud which would soon cause it to shear off.

35 By reference to the drawings it will be seen that the arrangement of the pivoted jaw is such that when the tool is brought into engagement with the object to be operated upon and pushed in the direction of the object, the pressure of the object against the pivoted jaw is such as to cause a force to be applied in the direction of the arrow (a) in Figure 2 40 which tends to swing the jaw in the clockwise direction and bring the lower contacting face toward the pipe P with pressure operating in the direction of the arrow (b), thereby insuring a tight contact of the tool with the 45 object at the three points (c), (d) and (e). In this way ample gripping contact is made with the surface of the pipe to tightly hold the same while being turned and thus prevent the wrench from slipping and consequently cutting the pipe.

50 In the manufacture of the invention the "finger" 6 and jaw 16 is preferably made of hardened or tool steel while the member 3 may be made of common steel, and the several parts 1, 3, 6 and 16 may all be die stamped and thus the cost of manufacture kept down to a minimum.

55 It will be noticed that the slot which forms the bifurcations 8 and the slot which forms the bifurcations 12 align with each other and may be made by a continuous cut during the process of manufacture, thereby reducing manufacturing costs to a minimum.

60 From the foregoing description, taken in connection with the accompanying draw-

ings, it is thought the complete construction, operation and advantages of my invention will be clear to those skilled in the art to which it relates.

70 What I claim is:

A wrench of the type described, comprising an arm having a hand at one end, said hand comprising a body portion, a fixed curved finger projecting forwardly therefrom in the general direction of the arm and a fixed thumb projecting laterally from said body portion and forwardly, said finger and thumb being separated to leave a crotch which extends in the general longitudinal direction of the arm, a pivoted jaw, and a stud pivoting said jaw to the end of said thumb to swing into and out of the crotch, said jaw having a working face and said finger having a working face cooperating therewith, said thumb having the inner corner part of its end curved to constitute a pressure receiving seat and said jaw having a shoulder cooperating with said seat, the pivotal connection between said jaw and said thumb being loose, said thumb having its end bifurcated and said jaw having an ear to fit said bifurcation, said ear having its end face curved on a radius having the pivot stud as a center, and said thumb having a seat to be engaged by said curved end face, whereby the thrusts will be received by said seats to take the wear off the pivot stud, said body portion and said finger being separate elements having a tongue and groove engagement, and means securing the same together, and said body portion and said arm being separate elements having a tongue and groove engagement and means securing the same together, said thumb being integral with said body portion.

CHARLES L. DUNHAM.
